[57] **CLAIM**

The ornamental design for a storage bracket for a cooking utensil lid, as shown and described.

DESCRIPTION

FIG. 1 is a perspective view of a storage bracket for cooking utensil lid showing my new design, the portion of a vertical surface, the lid, and the screw fasteners being shown in broken lines for illustrative purposes only,

FIG. 2 is a top plan view;

FIG. 3 is a front elevational view; and

FIG. 4 is a side elevational view taken from the right of FIG. 1.

FIG.1

FIG.2
